[57] CLAIM

The ornamental design for a vacuum cleaner latch, as shown and described.

DESCRIPTION

FIG. 1 is a top plan view of the first and second embodiments of our new ornamental design;

FIG. 2 is a front elevational view of the first and second embodiments;

FIG. 3 is a left side elevational view of the first embodiment;

FIG. 4 is a right side elevational view of the first embodiment;

FIG. 5 is a rear elevational view of the first embodiment;

FIG. 6 is a bottom view of the first embodiment;

FIG. 7 is a rear elevational view of the second embodiment;

FIG. 8 is a cross-sectional view taken along line 8—8 of FIG. 7;

FIG. 9 is a bottom view of the second embodiment;

FIG. 10 is a cross-sectional view taken along line 10—10 of FIG. 9; and,

FIG. 11 is a cross-sectional view taken along line 11—11 of FIG. 1.

The latch as illustrated and claimed is typically used for attaching the top cover to the bottom tank of a tank type utility vacuum cleaner.
